UNITED STATES PATENT OFFICE.

WILLIAM P. TRACY, OF GRAND RAPIDS, MICHIGAN.

THILL-COUPING.

SPECIFICATION forming part of Letters Patent No. 310,480, dated January 6, 1885.

Application filed May 16, 1884. (No model.)

To all whom it may concern:

Be it known that I, WILLIAM P. TRACY, of Grand Rapids, in the county of Kent and State of Michigan, have invented a new and useful Improvement in Shaft Couplings and Supporters; and I do hereby declare that the following is a full, clear, and exact description of the same.

My invention is an improved carriage-shackle, having for its object security against rattling, and to hold the shaft automatically in a vertical position when the carriage is not in use.

In the accompanying drawings, Figure 1 is a perspective view of my improved shackle. Fig. 2 is a vertical section through the same. Fig. 3 is a perspective view of one of the parts detached.

In these drawings, the bail C, formed with an eye for the pintle d, connects the shaft to the shackle. The shackle is attached to the axle in the usual manner, and is provided with ears e e of ordinary construction. The body of the shackle, however, is of special construction, as shown in the figures. It is formed with a plate, f, with a plane surface adapted to lie against the under side of the axle, and has preferably a small vertical flange, g, which bears against the front edge of the axle. Underneath the plate the enlarged part h of the shackle is chambered to receive a coiled spring, k. The rear end of the shackle is plugged with an adjusting-screw, l, by means of which the tension of the spring may be regulated.

A block, m, provided with a stud, 1, is adapted to fit between the ears, the stud projecting into the interior of the spring. The block has also upper and lower flanges, 22, so that it is securely held in place between the ears, and may slide freely backward and forward. It bears upon the spring, which has play enough to keep the block pressed forward against the eye of

the bail when the latter is held in place by the pintle. When the spring loses its elasticity, it may be set up by simply turning the nut in 45 the rear without the trouble of taking out and replacing the worn spring, as is the case in the spring-shackles in ordinary use. The front part of the block is formed to fit the rear end of the bail, and has also a transverse groove, 50 4, adapted to receive a transverse rib on the bail. This rib is so arranged that when the shaft is raised the rib presses back the block until it reaches the groove 4, in which it lodges and holds the shaft in a vertical position. 55 The construction is the same for both shafts, and these ribs serve to retain the shafts in an upright position when the carriage is not in use.

I do not limit myself to the particular construction or form of the shackle or block.

I claim as my invention—

1. A shackle adapted to fit the axle and chambered to receive a spring, a spring inserted therein, and a block fitted between the 65 ears of the shackle and interposed between the spring and the bail, all substantially as described.

2. A shaft-coupling and supporter consisting of a block fitted between the ears of the 70 shackle, a spring behind said block, and a suitable bail to connect the shaft to the shackle, the bail and block being provided with an interlocking rib and grooves, whereby the shafts are held in upright position, substantially as 75 described.

In testimony whereof I have signed my name to this specification in the presence of two subscribing witnesses.

WILLIAM P. TRACY.
